UNITED STATES PATENT OFFICE.

THEODORE N. LE CLAIRE, OF ST. PAUL, MINNESOTA.

DESIGN FOR A PUGILIST DOLL.

58,389.

Specification for Design.

Patented July 12, 1921.

Application filed September 4, 1920. Serial No. 408,368. Term of patent 14 years.

To all whom it may concern:

Be it known that I, THEODORE N. LE CLAIRE, a citizen of the United States, residing at St. Paul, in the county of Ramsey and State of Minnesota, have invented a new, original, and ornamental Design for a Pugilist Doll, of which the following is a specification, reference being had to the accompanying drawing, forming a part thereof.

The figure is a slightly perspective front elevation of a pugilist doll, showing my new design. It consists mainly of a base with a human figure in pugilistic attitude mounted thereon, and the arbitrary comic name "Puggy" marked on the base.

I claim:

The ornamental design for a pugilist doll, as shown and described.

In testimony whereof I affix my signature.

THEODORE N. LE CLAIRE.
